TREATMENT OF HYDROCARBON OILS

Jacque C. Morrell and Gustav Egloff, Chicago,
Ill., assignors to Universal Oil Products Com-
pany, Chicago, Ill., a corporation of South
Dakota

No Drawing. Application February 16, 1931
Serial No. 516,277

4 Claims. (Cl. 196—36)

This invention relates to the treatment of hydrocarbon oils, and refers more particularly to the refining of relatively low boiling hydrocarbon distillates at elevated temperatures, especially those resulting from the conversion of relatively high boiling hydrocarbons at elevated temperatures.

More specifically the invention comprises subjecting hydrocarbon oil vapors to treatment with the acids of phosphorus in the presence of solid contact materials of a non-metallic nature, such as fuller's earth, clays, bentonite, bauxite, crushed fire-brick, pumice stone and other materials of an earthy or siliceous nature. Oxygen-containing gases, such as air, oxygen, ozone alone or in combination, may also be employed in the treatment, ozonized air having been found to be particularly efficacious in some instances.

Owing to its varying valence, phosphorus forms an extended series of acids which correspond to the different oxides mixed with various molecular equivalents of water. The following table will give briefly the commoner acids of phosphorus:

25	H_3PO_3 ($P_2O_3 \cdot 3H_2O$)	Orthophosphorous	M. P. 70° C.; dec. 200° C.
	H_3PO_2 -----	Hypophosphorous	M. P. 26.5° C.; dec. above
	$H_4P_2O_6$ ($P_2O_4 \cdot 2H_2O$)	Hypophosphoric	M. P. 55° C.; dec. 70° C.
	$H_4P_2O_5$ ($P_2O_3 \cdot 2H_2O$)	Pyrophosphorous	M. P. 38° C.; dec. 130° C.
30	HPO_3 ($P_2O_5 \cdot H_2O$)	Metaphosphoric	Sublimes
	$H_4P_2O_7$ ($P_2O_5 \cdot 2H_2O$)	Pyrophosphoric	M. P. 61° C.
	H_3PO_4 ($P_2O_5 \cdot 3H_2O$)	Orthophosphoric	M. P. 38.6° C. - $\frac{1}{2}H_2O$ 213° C.

We have found that the different acids of phosphorus may be advantageously employed in the treatment of hydrocarbon oil vapors, particularly those formed from the cracking of relatively heavy hydrocarbon oil mixtures. It will be seen from a consideration of the table of properties of the acids of phosphorus that the nature of the treating effect may be varied over a considerable range by utilizing acids of different properties. By using acids containing highly oxidized anhydrides of phosphorus and substantial proportions of oxidizing gases mixed with oil vapors, distinct polymerizing effects may be produced, these effects extending in many instances to reaction upon the sulfur-containing hydrocarbons. With acids containing less highly oxidized phosphorus, or in other words, the oxides of phosphorus of a lower valence, the treating effect may be moderated so that controllable amounts of unsaturated compounds may be removed, such a treatment being particularly adapt-

ed to the refining of vapor phase or high temperature cracked distillates.

In some cases the contact masses may be mixed with minor amounts of materials of a basic nature, such as metals or their oxides, these resulting in some instances from the decomposition of salts of the metals incorporated with the earthy materials prior to their roasting and in other instances from the disintegration reactions of the earthy materials during their use in the process. The effect of the bases may be of a chemical or merely of a catalytic nature.

The invention is more particularly directed to the treatment of vapors of lower boiling cracked distillates, though straight run distillates may also be treated within the scope of the invention.

In applying the process of the invention to practice any suitable equipment may be employed which will permit contacting the mixture of hydrocarbon vapors, oxidizing gases and steam with the liquid or solid acids and the solid contacting or polymerizing materials; for example, a suitable tower or chamber packed with a selected mixture of contacting materials may be employed following the fractionator of a cracking system, the oxidizing gases and steam being introduced when used at a suitable point or points along the line of flow of the ascending or descending vapors. Similarly, any device which permits the efficient contacting of the mixture of oxidizing gases and hydrocarbon vapors undergoing treatment with the liquid or solid acids and the solid contact masses may be employed. The contact materials may sometimes be employed in successive strata of varying composition or supported on superimposed trays designed to produce intimate contact.

It has been found desirable to neutralize the vapors before or after condensation and to this end the vapors may be treated with ammonia gas or pass counterflow to solutions of alkalies in auxiliary neutralizing equipment, or the condensed vapors may be treated with liquid alkalies such as solutions of caustic soda, ammonia or the like, the traces of reagents and reaction products remaining being washed out with water when found necessary.

The amounts of reagents used in treatments comprised within the scope of the invention will vary with the character of the vapors treated, the temperatures and pressures employed and other factors. Amounts of phosphorus acids may be employed from a fraction of a percent by weight of oil treated to as high as 10% or higher in cases where relatively heavy treatments are desired.

Various temperatures of treatment may be employed, for example, from 250-600° F., more or less, and the pressures may be subatmospheric, atmospheric, or superatmospheric. While the results may vary with the conditions employed, the pressures and temperatures are chosen so that the hydrocarbons are treated substantially in the vapor phase.

As specific examples of the operation of the process of the invention and of the results obtained, a California cracked distillate of approximately motor fuel boiling range may be vaporized and subjected to treatment with orthophosphoric acid (see table) of approximately 80% concentration, the vapors being mixed with small amounts of air or oxygen and steam during their passage in a downward direction through a stationary mass of fuller's earth. The phosphoric acid may be used in an amount equivalent to approximately six pounds per barrel. Steam is used at the rate of approximately two pounds per barrel. The untreated product may show a gum content of approximately 500 mgs. per 100 ccs. and have a reddish-brown color, with a sulfur content of approximately 0.45%. The treated product after suitable separation from spent reagents, neutralizing with alkalies and washing with water may show a gum content of approximately 18 mgs. and a color of plus 30 on the Saybolt scale. The sulfur content may be found to be as low as 0.1%.

In the case of a mixed Mid-Continent and West Texas cracked distillate treated with approximately the same amounts of reagents, the gum content may be reduced from 300 mgs. to 10 and the color raised from a light amber to approximately 30 on the Saybolt scale. The sulfur content may be reduced from 0.4% to 0.2% approximately.

The process of the invention is particularly suitable to the treatment of cracked distillates produced from California oils. In some cases the untreated distillates may contain 700 mgs. of

gum and have a dark reddish color, while the treated distillates may have a gum content of only 60 mgs. and a color of 25 to 30 on the Saybolt scale. The sulfur content may be reduced from 0.4% to 0.1%.

The foregoing description and examples have disclosed a process applicable to the treatment of hydrocarbon oil vapors which has a wide applicability and is capable of great variations in the methods of operation and the amounts of reagents employed. Therefore, the specific cases cited are not to be construed in a limiting sense upon the broad scope of the invention, as many other modifications and examples can be given.

We claim as our invention:

1. A step in the refining of the overhead products resulting from the cracking of hydrocarbon oil, which comprises subjecting said products in heated vaporous condition to the action of an acid of phosphorus and a free oxygen containing gas in the presence of a non-metallic solid contacting agent.

2. A step in the refining of the overhead products resulting from the cracking of hydrocarbon oil, which comprises subjecting said products in heated vaporous condition to the action of an acid of phosphorus and a free oxygen containing gas in the presence of bauxite.

3. A step in the refining of the overhead products resulting from the cracking of hydrocarbon oil, which comprises subjecting said products in heated vaporous condition to the action of an acid of phosphorus and a free oxygen containing gas in the presence of fuller's earth.

4. A step in the refining of the overhead products resulting from the cracking of hydrocarbon oil, which comprises subjecting said products in heated vaporous condition to the action of an acid of phosphorus and a free oxygen containing gas in the presence of a zeolite.
